UNITED STATES PATENT OFFICE.

ERNEST NORMAN AND RAYMOND R. AMES, OF NEW YORK, N. Y.

DESIGN FOR A BAG-FRAME.

59,030.

Specification for Design.

Patented Sept. 13, 1921.

Application filed November 2, 1920. Serial No. 421,422. Term of patent 3½ years.

To all whom it may concern:

Be it known that we, ERNEST NORMAN and RAYMOND R. AMES, citizens of the United States, and residents of the city of New York, borough of the Bronx, in the county of Bronx and State of New York, have invented a new, original, and ornamental Design for Bag-Frames, of which the following is a specification, reference being had to the accompanying drawing, forming part thereof.

The figure is a side elevation of a frame for laundry bags, shopping bags, work bags, or similar devices, the location of the mouth of the bag with respect to the frame being indicated in dotted lines.

We claim:

The ornamental design for a bag frame, as shown.

ERNEST NORMAN.
RAYMOND R. AMES.
